ANIMAL SECURING GATE

Cecil L. Tansel, Rte. 4, Box 165, Chandler, Okla. 74834

Filed July 3, 1972, Ser. No. 268,881

Term of patent 14 years

Int. Cl. D30—99

U.S. Cl. D30—99

FIG. 1 is a perspective view of an animal securing gate, showing my new design;

FIG. 2 is a front elevational view;

FIG. 3 is a side elevational view, the opposite side being substantially a mirror image thereof;

FIG. 4 is a top plan view; and

FIG. 5 is a bottom plan view thereof.

I claim:

The ornamental design for animal securing gate, substantially as shown and described.
